UNITED STATES PATENT OFFICE.

WILLIAM H. LEGATE, OF HARTFORD, CONNECTICUT.

METHOD OF MAKING RADIATORS.

1,170,915.

Specification of Letters Patent.

Patented Feb. 8, 1916.

Application filed May 27, 1915. Serial No. 30,756.

To all whom it may concern:

Be it known that I, WILLIAM H. LEGATE, a citizen of the United States, residing at Hartford, in the county of Hartford and 5 State of Connecticut, have invented certain new and useful Improvements in Methods of Making Radiators, of which the following is a specification.

This invention relates to a method of 0 making radiators.

The method can be practised with facility and ease and by it I can inexpensively produce a radiator which is light yet thoroughly strong, and the parts of which can 5 be quickly and easily taken apart for any purpose.

The method involves other features of novelty and advantage which with the foregoing will be stated at length in the following 0 description, wherein I will set forth in detail that one of the several convenient forms of embodiment of the invention which I have selected for illustration in the drawings accompanying and forming part 5 of the present specification. I do not restrict myself to this exact disclosure; I may depart therefrom in several respects within the scope of the invention defined by the claims following said description.

0 Referring to said drawings: Figure 1 is a perspective view of a radiator made in accordance with my method and involving my invention and as viewed from the inside or back thereof. Fig. 2 is a front elevation of 5 one side of said radiator. Fig. 3 is a vertical sectional view of the same. Fig. 4 is a perspective view of a mold. Fig. 5 is a detail with parts broken away of a portion 0 of a core. Fig. 6 is a perspective view of a tubular member showing a way of removing the core therefrom. Fig. 7 is a sectional 5 elevation of a part of the body of the radiator with the incased core. Fig. 8 is a sectional view of a portion of the body of the 0 radiator, and Fig. 9 is a similar view showing more of the body, the interior skin or coating not being shown in Fig. 9, but appearing in Fig. 8 for the reason that the latter is on a larger scale than the former.

0 Like characters refer to like parts throughout the several views, which it will be noted are on different scales.

A radiator made in accordance with a method involving my invention can be employed with utility in widely different connections, although it is of particular ad-

vantage when employed in conjunction with or forming part of the equipment of an automobile, providing as will be understood, the necessary water to keep the engine in a 60 relatively cool condition. The radiator includes a body of grid-like tubular construction and a crown or head pan and a settling or base pan suitably associated together as will hereinafter appear. The "body" as I 65 have termed it, is made through the intervention of a core of some suitable material such as a lead composition which can be easily fused, for instance at a temperature of 202 degrees Fahrenheit. This body has 70 deposited upon it for instance, electro-chemically, a metal which may be either copper or brass, the former being quite advantageous. After the metal is deposited on the core, the core is removed, for instance 75 by heat, leaving the grid-like tubular body, and when a lead composition is provided the lead will coat the interior of the tubular like body with a protective skin.

With the foregoing general observations 80 I will now describe more in detail what is illustrated in the annexed drawings. Initially or at some primary stage in the process I utilize a grid-like member which is of such character as to be subsequently removed from a body formed on it. If the external body be of copper, for instance, this grid would preferably be fusible. For example the grid-like core can advantageously consist of some lead composition 85 which will fuse as already noted at about 202 degrees Fahrenheit. In Fig. 4 I have shown a mold 2 which is made of some suitable material, bronze answering satisfactorily in this respect. The sections of the 90 mold have longitudinally extending channels 3 closed at their ends and transversely extending channels 4 intersecting the longitudinally extending channels, the channels in the mold sections mating to produce 95 passages fully circular in cross section. From the outside channels in the body section of the mold the bores 5 depend, these bores 5 being fully circular in cross section. The mold has the gate 6 into which the 100 metal to form a grid is poured. When the sections of the mold are closed together molten metal is poured into the mold by way of the gate 6, and it fills the spaces so as to produce a grid such as that denoted 105 in a general way by 7. The mold and the grid therein have been shown of compara-

tively small size, this for economy in space and simplicity of illustration. It is a matter of fact however, that there may be any number of longitudinally extending and any 5 number of transversely extending bars in a grid as 7. In Fig. 4 the upper section of the mold is swung up so that the grid 7 can be removed therefrom if cool. Before forming the body of the radiator the fin 8 left by casting is removed from the grid 7. It will be clear that said grid comprises a number of longitudinally extending and a number of transversely extending bars or rods, and although these are circular in cross section, it is not necessary that they be made in such shape, although such form is advantageous, in that no angles are presented in the body of the radiator in the length of the tubes thereof. In addition to the longitudinally extending and transversely extending rods or bars of the grid 7 there are 10 projections as 9. As represented these projections 9 extend from the side bars of the grid.

25 After the formation of a grid it is brought opposite a mating grid as shown for example in Fig. 7 with the flat ends of the projections 9 into abutment as shown on the left in Fig. 5. When this is accomplished 30 the projections are soldered or otherwise suitably united as shown on the right in Fig. 5 so as to produce a duplex grid. As a matter of fact there may be any number of these fusible grids connected together. The 35 connected grids are then coated with the necessary metal which is to form the tubular body of the radiator, and copper or brass answer satisfactorily in this respect, copper in fact being preferable. After the two 40 grids 7 have been united, or after the sections of the fusible core have been connected together as it might otherwise be put, the core is in readiness to be coated, for example by being immersed in a hot copper sulfate 45 solution, copper being deposited electrolytically upon the core to the requisite thickness, for illustration somewhere between twenty to forty thousandths of an inch thick. After the core is plated, it is taken 50 from the bath and cleaned, subsequent to which it is put in an oven and subjected to heat of approximately 202 degrees Fahrenheit, which melts the core, the core in molten condition running from the tubular body as 55 shown in Fig. 6 which might be assumed to represent one of the longitudinally extending tubes 10 of the radiator body denoted in a general way by 11. There will be two series of such longitudinally or vertically 60 extending tubes 10, one at the front and the other at the back of said body, the side tubes of the two series being united by connecting tubes 12. The longitudinally or vertically 65 extending tubes 10 are connected by transverse tubes 13. As will be inferred there

may be any desired number of these longitudinally extending tubes 10 and the same observation applies with respect to the transversely or laterally disposed tubes 13. In like manner it is not essential that the 70 connecting tubes 12 as I have termed them connect the side tubes of the front and rear series of tubes, although this construction is desirable. The radiator body 11, as will be clear, comprises a front tubular grid and a 75 rear tubular grid in communication with each other by way of connecting tubes, all the tubes in fact being in communication with each other to provide for the proper circulation of the cooling liquid which when 80 the radiator is used on an automobile would be water under ordinary circumstances. While the longitudinally and transversely extending and connecting tubes of the body 11 are disposed at right angles to each other, 85 this may not always be necessary. It will be clear that all the tubes when a fusible core is utilized in the formation of said body, are interiorly coated with the fusible material, sufficient of the material remaining 90 for this purpose. Fig. 9 represents a portion of the body 11. The tubes are not shown coated, the coating being omitted on account of the smallness of scale of this particular view. Fig. 8 is on a larger scale 95 and shows the coating in the tubes of the body. The interiorly coated shell-like or hollow body is now in readiness for assemblage with the remaining parts of the radiator. In addition to the body 11, said radiator comprises a base or settling tank or 100 pan 14 and a crown tank or pan 15. The upper or head tank is provided with a discharge nipple or tube 16 adapted to be connected in some suitable way with the water space of the engine, this water space delivering in turn through suitable connections with the nipple or tube 17, the water after it has exercised its function. This nipple or tube 17 is connected with the base or settling tank 14. The upper tank 15 is provided with the removable screw-threaded cap 18 such as is commonly used in automobile radiators, and in addition is provided 105 with the customary overflow pipe 19.

110 The lower pan 14 and upper pan 15 are usually cast integral, their inner walls being perforated near the front and rear thereof to receive the upper and lower terminals of the longitudinally extending rods 10 of the reticulated or foraminous hollow or tubular body 11, said terminals being soldered or welded or otherwise secured in the respective perforations. Preferably formed integrally 115 with the lower pan 14 are the side members 20 of practically duplicate construction and which present in fact the sides of the radiator. The ends of the upper pan or tank 15 are rabbeted or channeled as at 21 to receive the upper ends of the side members 20, 120 125 130

said side members being fastened to the upper pan in any desirable manner as by screws 22 tapped into the end portions of said upper pan 15. The heads of the screws 5 are countersunk in said side members 20 and after the screws have been driven home solder 23 will be flowed into the slots of the screws. The side members 20 have as shown inwardly extending flanges, the upper ends 10 of which abut against the bottom of the pan 15 to aid in upholding the pan, the flanges overlying the front of the radiator body 11 at the sides thereof. The upper ends of the side members 20 it will be noticed 15 abut against the tops of the rabbets 21 to further aid in upholding the pan 15. It will be clear, therefore, that the flanges 24 are not coextensive with the side members 20 but extend short of the upper ends 20 thereof. It will be clear that there is a radiating surface of considerable extent. The radiator is light yet possesses unusual strength. It consists practically of merely 25 three parts. It can be easily taken apart for repair or other purposes. Water can freely circulate longitudinally and laterally of the body 11 uniformly reaching all parts thereof. Owing to the construction of the body there is provision for thorough circulation 30 of air therethrough to aid in maintaining the water cool.

What I claim is:

1. A method of making radiator bodies comprising the formation of two grid-like cores, each having longitudinally and transversely extending bars, then connecting the two cores with a space therebetween, then depositing a metal on both the cores, and

then removing the cores from the exterior structure.

2. A method of making radiator bodies comprising the formation of two grid-like cores having projecting means, then uniting the projecting means to form two connected cores, then depositing a metal on the cores, 45 and then removing the cores from the exterior structure.

3. A method of making radiator bodies comprising the formation of two grid-like cores, each having longitudinally and transversely extending bars and each also having projections extending inward from the barred portion thereof, then uniting the projections, then depositing a metal on the two cores and on the connected projections, 55 and then removing the cores and said projections from the exterior structure.

4. A method of making radiator bodies comprising the formation of fusible grid-like cores each having longitudinally and transversely extending bars and also having projections extending inwardly from the barred portion thereof, uniting said projections, then electrolytically completely enveloping said longitudinally and transversely extending bars with a metal between the ends thereof and also enveloping said projections, and then removing the core by heat from the exterior structure.

In testimony whereof I affix my signature 70 in presence of two witnesses.

WILLIAM H. LEGATE.
